UNITED STATES PATENT OFFICE.

FREDERICK J. FRENZ, OF AVALON, PENNSYLVANIA.

HEATING SYSTEM.

Application filed August 20, 1924. Serial No. 733,093.

This invention relates to heating systems, and has for an object the provision of a heating furnace or boiler particularly of the hot water type which is simple in construction, 5 easy to manufacture and efficient in operation.

Another object of the invention is to provide a furnace with means between the fire box and the heating chamber for automatically regulating the size of the passageway connecting them.

Another object of the invention is to provide a water cooled draft regulator for a heating furnace or boiler.

Another object of the invention is to provide a heating furnace or boiler with means for admitting air to the fire box adjacent the passageway between the fire box and the heating chamber whereby the gases from the burning fuel and the air are properly mixed to produce a combustible mixture which will ignite in the fire box and pass into the heating chamber in the form of a flame thus utilizing these gases to produce heat, which gases would ordinarily pass into the heating chamber in the form of smoke with the consequent loss of heat, objectionable soot and other deposits on the fluid conducting tubes within the heating chamber.

A further object of the invention is to provide a heating furnace or boiler having an air duct for conducting heated air from the ash pit to the firebox above the fuel.

A still further object of the invention is to provide a heating furnace or boiler with an automatically movable fire control means and an air controlling means which is automatically operated by the fire control means.

Heretofore smokeless furnaces or boilers have been constructed and installed to meet the requirements of the most severe seasonal demands and are consequently operating in either a greatly choked manner over the major part of the heating season or else the furnace is always operating at its maximum, whether necessary or not, in either case there is a great loss of fuel and poor combustion, which would produce a great amount of objectionable smoke, and another object 45 of the invention is to provide a furnace with means whereby the air fed to the fuel bed is automatically controlled by the heat of the fire, thus providing a furnace which will automatically adjust itself to meet the seasonal demands without sacrificing the smoke-

less feature and economical and efficient operation of the furnace.

These and other objects will be apparent from the following description:

Referring to the drawings in which like reference characters refer to like parts, Fig. 1 is a sectional view of a furnace embodying my invention, Figs. 2, 3 and 4 are front, back and side elevational views respectively of the same; Fig. 5 is a fragmental sectional view 65 taken on the line 5—5 of Fig. 1; Fig. 6 is an enlarged detail sectional view of a portion of the furnace illustrating a modification of the fire control member and Fig. 7 is a sectional view of the same taken on the line 7—7 of 70 Fig. 6.

Referring now in detail to the drawings the reference character 1 indicates the heating furnace which, as illustrated in the drawings, is preferably of the boiler or hot water type and having a fire box 2, an ash pit 3 and a heating chamber 4, there being the usual grate bars 5 between the ash pit and the fire box and there also being a crown sheet 6 between the fire box and the heating chamber.

The lower portion of the furnace in which the fire box, ash pit and a portion of the heating chamber is formed, preferably comprises members 7 and 8. Each of these members has a wall 9 which forms one of the side walls 75 of the lower portion of the furnace and vertically disposed walls 10 and 11 which form a part of the front and back walls respectively of the lower portion of the furnace. Some distance below the top of each wall 9 a crown sheet member 12 is provided which is integral with the wall 9. When the parts 7 and 8 are secured together the members 12 form the crown sheet 6 between the fire box 80 and the heating chamber which crown sheet extends in one direction from one wall 9 to the other and inwardly from the front wall to a point some distance from the back wall, and forms the top of the fire box. At the top of the walls 11 of the parts 7 and 8, horizontally disposed portions 13 are provided, each of which is integral with one of the walls 11.

At their meeting edges, these portions are interlocked by means of projecting portions 14 engaging each other. The wall 10 is located below the crown sheet 6 and the upper edge thereof, together with the outer portion of the crown sheet forms an opening 10^a 100 through which fuel may be passed into the firebox, such opening being provided with a 110

door 15 of any suitable form which is hinged to a plate 16 in any preferred manner. This plate 16 extends above the crown sheet 6 and adjacent the upper surface of this crown sheet is provided with an opening 17 into the heating chamber, which opening is controlled by a door 18 preferably hinged on the plate 16, such opening being for the purpose of removing dust or other foreign matter from the top of the crown sheet 6. Below the wall 10 a plate 19 is provided having openings 20 and 21 formed therein, which are controlled by doors 22 and 23, respectively, the opening 20 being for the purpose of removing clinkers or the like from the grate bars 5, the front portions of which are rotatably mounted in the plate 19 between the openings 20 and 21, and the door 23 being for the purpose of removing ashes from the ash pit. The plates 16 and 19 serve to form part of the front wall of the bottom portion of the furnace and are secured to the front portion of the walls 9, crown sheet member 6 and wall 10 and thus serve to connect the parts 7 and 8 against separation. The walls 9, 10 and 11, crown sheet members 12 and horizontally disposed portion 13 are provided with inner and outer walls which walls are spaced apart to provide fluid heating and circulating spaces 9a. The heating chamber is preferably located above the fire box 2 and comprises a front wall 24 which is preferably secured to the plate 16, a top wall 25 which at one end is connected with the front wall 24 through the medium of a plate 26 and bolts or other securing means, a back wall 27 which comprises connected plates 28 and 29 and side walls 29a. All of these walls are lined with asbestos 30 or any other suitable insulating medium. Within the heating chamber a part of the circulatory system is arranged which comprises a plurality of vertically disposed tubular members 31 which are arranged in staggered relation, the lower end portions of each of which extends into openings formed in the top of the portion 13 of the wall 11. Near the front wall of the heating chamber a plurality of vertically disposed tubular members 32 are provided which are also arranged in staggered relation, the lower ends of these members being closed and the upper ends opening into a manifold 33 arranged above the furnace and outside of the heating chamber which manifold opens into the pipes 34 which conduct the heating fluid to the radiators, which are of any suitable type and located in any desired positions. Extending between and opening into the members 31 and 32 are tubular members 35 which may be of any suitable size and which slope upwardly from the members 31 to the members 32 thus permitting the heated fluid which is contained therein to rise and flow into the members 32 and then into the heating system remote from the furnace.

Within the heating chamber baffle plates 36 and 37 are provided which, together with the crown sheet form a tortuous passageway, as indicated by the arrows in Fig. 1 of the drawings, for the heat and gases which rise from the fire box, thus conducting the heat so that it will be utilized over the maximum heating surface of the fluid conducting members 31, 32 and 35, before reaching the flue opening 38 which leads from the upper back portion of the heating chamber to the atmosphere.

At each side of the furnace a tubular member 39 is provided, the lower end portion of which extends into the hollow portion of one of the walls 9 and the upper portion opens into and is connected with the manifold 33. These members are for the purpose of conducting the fluid which has become heated in the hollow walls of the bottom portion of the furnace, i. e., in the hollow wall portions forming the fire box 2, to the manifold 33, where the fluid mixes with the fluid which comes from the tubular members in the heating chamber as hereinbefore described.

At each side of the furnace a tubular member 40 is also provided, the lower end portion of which extends into the lower portion of one of the walls 9, the upper portion being connected with the return pipe from the portion of the heating system remote from the furnace and is for the purpose of conducting the cooled water into the lower portion of the furnace where it is reheated and again passes upwardly into the heating system remote from the furnace.

The crown sheet 6 extends inwardly from the front of the furnace and terminates some distance short of the upper portion of the wall 11, and this crown sheet together with the upper portion of the wall 11 form an opening 41 through which the flame, heat and gases are adapted to pass into the heating chamber, such opening preferably extending across the furnace from one of the walls 9 to the other.

For the purpose of controlling the size of the opening 41 a bodily movable member 42 is provided, one side of which member is provided with a projection 43 which is movably mounted in a slot 44 formed in the side wall 9 of the part 7, and at the opposite side is provided with a hollow member 45 which is slidably mounted in a slot 46 formed in the side wall 9 of the part 8. This member 42 is hollow and extends through an opening 47 formed in the wall 11 and is disposed at an angle to such wall and crown sheet 6. At its lower end this member 42 is provided with an opening in which the upper end of a flexible fluid conducting member 48 is secured, the lower end of such member 48 being secured in the wall 9 adjacent the lower end thereof. The member 45 is connected with the upper portion of the wall 9 of the part 8 through the medium of a flexible connection 130

49 such connection being covered by a pan shaped plate 29^b which is secured to the wall 9. It will here be noted that as the fluid contained in the member 42 is heated it will pass 5 upwardly through the member 45 and flexible connection 49 into the upper portion of the side wall 9 and the cool fluid will be caused to pass from the lower portion of the wall 11 through the flexible connection 48 10 into the lower portion of the member 42, thus providing for a circulation of fluid which keeps the member 42 cool and prevents such member from warping or bending, due to intensive heat from the fire box to which it is 15 subjected.

To advance the member 42 toward the crown sheet 6 and to retract it, in order to vary the size of the opening 41, a bodily movable shaft 50 is provided which has adjacent 20 each end thereof a toothed wheel 51 which is adapted to interengage with a toothed rack 52 which is preferably arranged below the member 42 and is inclined upwardly and preferably parallel with the member 42. 25 The under side of this member 42 is provided with teeth 53 which are also adapted to interengage with the toothed wheels 51. To keep the teeth 53 on the member 42 in engagement with the teeth of the wheels 51, rollers 54 30 are provided which are adapted to engage the upper surface of the member. For the purpose of rotating the shaft 50 a lever 55 is provided adjacent one end of the shaft, the lower portion 56 of which is of segmental 35 form. The shaft 50, wheels 51, racks 52, and operating lever 55 are arranged back of the wall 11 and below the horizontal portion 13 of such wall, and is enclosed by the back plate 29, there being a door 57 provided in the 40 plate 29 which, when opened will lend easy access to the mechanism which operates the member 42. For the purpose of rotating the shaft 50 a flexible member 58 is provided, one end of which is attached to the lever 55 and 45 for a portion of its length engages the segmented portion 56 of the lever; the opposite end of such flexible member being connected with a lever 59 which is operated by a thermostatic valve 60 in the manifold 33 which 50 valve may be of any suitable type.

The opening in the wall 11 through which the member 42 passes is somewhat larger than the thickness of the member 42 so that when this member is mounted in the slots 44 and 46 55 and on the toothed wheels 51 there is a clear space between the member and the part of the wall forming the lower boundary of the opening 47. This space is provided for the purpose of admitting air to the fire box above the fuel adjacent the member 42. The air admitted through this opening mixes in the fire box with the gases rising from the fuel and forms a combustible mixture which ignites 60 and burns inside the fire box or as it enters 65 the heating chamber, thus it will be seen that

the gases which would ordinarily go to waste are utilized to their fullest extent with the result that the fluid in the circulating system is heated to a higher degree for a given amount of fuel burned than has heretofore been possible. For the purpose of conducting air to the opening 47 a duct 61 is provided which leads from the ash pit 3 to the opening, there being a control door 62 between the ash pit and the opening whereby the flow of air to the fire box may be regulated. This door is pivotally mounted on a hollow member 63 in the duct 61, to move back and forth across the duct. This door is so formed and mounted that it will always have a tendency to move to its open position as illustrated in full lines in Fig. 7. For the purpose of operating this door a mechanism is provided which comprises a sheave 64 or other suitable member which is mounted on the shaft 50 and is adapted to rotate and move bodily therewith. To connect this sheave and the door 62 a flexible member 65 is preferably provided, one end of which is attached to the sheave and the opposite end to a flange or lug 66, on the door 62. It will here be noted that as the shaft is rotated and the member 42 advanced toward the crown sheet, the flexible member will be caused to wind upon the sheave thus causing the door 62 to be moved toward its closed position, and as the shaft is rotated in the opposite direction the flexible member will be caused to unwind, thus permitting the door 62 to move by gravity toward its open position. Should it be desired at any time to close the door a greater extent than it is moved automatically, or to move the door entirely by manual power, another flexible member 67 is provided, the outer end of which extends outside of the furnace where it is convenient to operate, and the inner end is attached to the lug 66 on the door 62.

The air taken from the ash pit and conducted through the duct 61 will be hot so that as it enters the fire box it will be nearer the temperature of the gases rising from the fuel than if cold air were conducted from outside of the furnace, thus rendering a thorough mixture of the gases and air to form a combustible mixture. By leading hot air to the fire box 115 there is no cooling effect of the heating chamber as would be the effect if cold air were conducted into the fire box. Further, by the use and control of hot air the mixture is rendered more combustible thus substantially eliminating smoke and consequent deposit of soot and tarry substance on the tubes of the circulating system in the heating chamber. It will here be noted that the heated air from the ash pit is conducted to and distributed at the most effective point, i. e., above the fire and preferably adjacent the fire control member, thus insuring a proper supply of air at all times for supporting efficient, economical and smokeless combustion above the fuel. 120 125 130

In Figs. 6 and 7 a modification of the controlling member 42 has been illustrated in which channels or grooves 68 are provided to allow a greater amount of air to pass into the fire box. This member is shown having two channels formed in its underside but it is to be understood that any number of channels of suitable size and shape may be provided. It is to be understood also that any means of admitting air to the fire box adjacent the control member is within the scope of the appended claims.

When it is desired to burn gas or oil in the furnace instead of coal, suitable burners, (not shown) are placed in the fire box which burners may be controlled by the usual valves 69 which valves are preferably of the needle type, the flow of gas being controlled by a valve 70 which is operated by the thermostat 60 by means of the lever 59 connected with the thermostat, a lever 71 connected with the valve 70 and the flexible connection 58 connected with both levers. When gas is used instead of coal the flexible connection 58 is disconnected from the lever 55 below the lever 71, thus rendering the fire control member 42 inoperative. It will be noted that when gas is used the control member is not needed and the opening is in wide open condition, nor is there any need of air being admitted to the fire box through the opening 47 for the gas and air is mixed in the usual mixers combined with the valves 69.

When coal is used as a fuel in the furnace it is desirable that the combustion be as complete as possible, and at the same time keep it under control so that the water in the circulating system will be kept at substantially an even predetermined temperature. Assuming that the water in the system is cold, the control member 42 will be in its normal inoperative position as shown in full lines in Figs. 1 and 6 and remains in this position until the temperature of the water is raised, at which time the thermostat 60 will cause the lever 59 to move as indicated by the arrow A in Fig. 4, thus causing the flexible member 58, due to its being mounted on the fixed pulleys 72, to move upwardly. This upward movement causes the operating lever 55 and shaft 50 to rotate in the direction as indicated by the arrow "B" in Fig. 1 and as they are rotated the toothed wheels 51 which rotate with the shaft will, by reason of their engagement with the teeth on the racks 52, be caused to move bodily upwardly, and as the shaft is rotated as it is moved bodily, the toothed wheels, due to their engagement with the teeth 53 of the member 42, will cause such member to be advanced in a direction across the opening 41, that is to say, the member 42 will be moved to restrict the opening 41, thus having the effect of damping the fire in the fire box. As the member 42 is moved in the direction as just

described the flexible member 65 winds up on the sheave 64 which causes the door 62 to be moved toward its closed position. It will here be noted that as the member 42 is moved in a direction across the opening the burning of the fuel in the fire box will be checked and the amount of gases rising from the fuel will be lessened and at the same time the supply of air through the duct 61 will also be lessened in proper proportion automatically and that the proper mixture of air and gas is maintained at all times. Assuming now that the member 42 has moved to its closed position as shown in dot and dash lines in Fig. 1 and the fire has been damped to such an extent that the temperature of the fluid in the heating system has dropped to a predetermined point the thermostat 60 will cause the lever 59 to be moved in the direction opposite to that indicated by the arrow A in Fig. 4, thus permitting the flexible member 58 to move downwardly which permits the member 42 to move by gravity toward its open position and as it moves in this direction it will drive the shaft 50 in a direction opposite to that indicated by the arrow "B" in Fig. 1 which causes the flexible member 65 to move downwardly, and permits the door 62 to move by gravity toward its open position. It will be noted from the foregoing that the control of the furnace is entirely automatic. It will further be noted that by automatically operating the member 42 and thereby controlling the supply of air through the duct 61, the proper amount of heated air will be permitted to enter the fire box through this duct, needed to insure the proper combustion above the fuel, thus the heat from the fire causes the supply of air to be controlled in such a manner that no matter what the demand on the furnace is, the supply of air will be just that needed by the fire to support proper combustion. It will still further be noted that when coal is used as a fuel, the ash pit door is in open condition at all times, and the member 42 which is caused to move by the heat from the fire will control the draft through the furnace in such a manner that the proper amount of air will be conducted through the ash pit door and through the fuel to support proper combustion.

When gas or oil is used as fuel the thermostat will cause the lever 59 to move upwardly or downwardly, which upward movement will cause the lever 71 to move upwardly causing the valve 70 to shut the gas off gradually, and downward movement permitting the lever 71 to move downwardly by gravity to turn the gas on. When gas or oil are used the valves 69 are suitably adjusted and to prevent the fuel from being entirely shut off a by pass 73 is provided around the valve 70, which by pass is provided with a regulating valve 74.

It will be noted that as the parts of the furnace forming the fire box are hollow, the temperature of the water within such parts will be raised considerably before it passes into the tubular members in the heating chamber or into the manifold outside of the furnace thus heating a maximum quantity of water by the burning of a minimum amount of fuel and will insure a maximum amount of water to circulate through the heating system.

It will be apparent to those skilled in the art to which this invention appertains that changes may be made in the details and arrangement of the parts forming the invention without departing from the spirit and scope of the appended claims.

Having thus described the invention, what I claim as new and desire to secure by Letters Patent is:—

1. In a heating furnace, a fire box, a heating chamber, an ash pit, a member movable between said box and chamber for controlling the draft through said furnace, means for automatically moving said member and means automatically operated by the first mentioned means, for controlling and admitting air to said box adjacent said member.

2. In a heating furnace, a fire box, a heating chamber, a member movable between said box and chamber, means for moving said member to control the draft through said furnace, means whereby air is admitted to said fire box beneath and adjacent said member and means movable by the first mentioned means for controlling the supply of air to said fire box as said member is moved.

3. In a heating furnace, a movable control member, teeth on said member, a toothed rack below said member, a rotatable and bodily movable operating shaft between said rack and member, means on said shaft engaging the teeth on said rack and member for moving said member and shaft as said shaft is rotated, and means for automatically rotating said shaft.

4. In a heating furnace, a fire box, an ash

pit, a heating chamber communicating with said box, a control member movable between said box and chamber, means whereby air is conducted from said ash pit to said fire box adjacent said member, and means for simultaneously operating said member and controlling the supply of air to said fire box.

5. In a heating furnace, a fire box, an ash pit, a heating chamber communicating with said fire box, a control member movable between said fire box and heating chamber, means for conducting air from said ash pit to said fire box adjacent said member, and means for controlling the supply of air to said fire box, the last mentioned means being operated simultaneously with said member.

6. The combination with a heating furnace, of a fire box, and a heating chamber, walls forming the sides of said fire box and having water heating chambers, a crown sheet forming the top of said box, said walls and crown sheet forming a communicating opening between said box and chamber, a member for varying the effective size of said opening and having a water heating chamber, said member being mounted to move through an opening formed in one of said walls, means connecting the water heating chamber of said member with the water heating chambers formed by said walls and means for moving said member.

7. In a heating system, a fluid heating furnace, comprising a plurality of connected hollow members forming a fire box, a heating chamber above said fire box, a crown sheet between said box and chamber, said members and crown sheet forming an opening between said box and chamber, a member mounted to move through an opening formed in said members in directions across the first mentioned opening for varying the size thereof, mechanism for operating said member, and means caused to operate by the temperature of the fluid for causing said mechanism to operate.

In testimony whereof, I affix my signature.

FREDERICK J. FRENZ.
